UNITED STATES PATENT OFFICE.

HENRY LAUGHLIN, OF HORTON, MICHIGAN.

GATE-HINGE.

1,332,851.

Specification of Letters Patent. Patented Mar. 2, 1920.

Application filed August 16, 1919. Serial No. 318,015.

To all whom it may concern:

Be it known that I, HENRY LAUGHLIN, a citizen of the United States, residing at Horton, in the county of Jackson and State of Michigan, have invented a new and useful Gate-Hinge, of which the following is a specification:

The present invention relates to gate hinges; its principal object is to provide a hinge which will permit the gate to be slideable longitudinally to a partly opened position as well as to support the gate for swinging movement.

A second object of the invention is to provide a gate hinge which will permit the gate to be moved longitudinally and which when being closed or extended only requires the gate to be moved a certain distance, the gate traveling to full closed position by gravity.

It is a further object of the invention to provide a gate hinge which includes a swinging trackway which is engageable with the gate after the same has been moved longitudinally to open position to assist the swinging trackway to support the gate and to prevent the same from moving accidentally in the trackway.

Another general object of the invention is to provide a gate hinge having the above characteristics which is simple in construction, which consists of few parts, and which may be manufactured and sold at minimum cost.

With the above and other objects and advantages in mind, the invention consists of the combinations of elements constructions and arrangement of parts, operations and general assemblage all of which will be hereinafter enlarged upon and set forth in the appended claims, the invention being illustrated in the attached drawings, wherein:

Figure 1. is an elevation of my improved hinge assembled with a gate, the gate being shown in an extended position and parts thereof broken away;

Fig. 2. is an elevation showing the gate in closed position; and

Fig. 3. is an elevation taken at the left end of Fig. 2, parts of the post being broken away, the gate being shown in open position.

Referring to the drawing in detail the gate is designated at 5 and is of usual construction.

The hinge consists of a pair of parallel rods the forward ends of which are bent downwardly at an oblique angle and are con-

nected together by rod section 11 through the medium of a coupling 12. These bars are connected adjacent their rear ends by a brace 13. The inner end of the uppermost bar terminates in a bearing 14 disposed upon the uppermost pintle 15 of a plurality of such pintles extending from a standard 16 the lowermost bar having its inner end curved downwardly and terminates in a laterally extending bearing 17 disposed upon one of the pintles 15.

There is provided an angularly disposed brace rod 18, the inner end of which terminates in a bearing 19 engaged upon the lower pintle 15 while its opposite end is engaged in the adjacent coupling or union 12 that connects the rods 10 and 11 together. An enlargement 20 is formed adjacent of the outer extremity of this rod 18 and terminates in a forwardly projecting extension 21. This extension is engageable with a lug 22 formed upon the plate 23 and attached upon the gate 5 when the gate has been moved longitudinally to partly open position.

Supported in a hanger 24 on the gate 5 is a grooved roller or wheel 25 which engages the rods 10 and traverses the same upon the longitudinal movement of the gate.

This embodiment of the invention is illustrative only and it will be understood that the same may be modified in many respects and that such limits of modification are only governed by what is claimed.

What is claimed is:

1. The combination with a gate and a roller disposed adjacent the inner end thereof, of a swinging trackway supporting the roller, a plate carried by the gate provided with an outstanding lug and an extension carried by the trackway upon which the engaged lug rests when the gate has been moved to one side of the trackway.

2. The combination with a gate, of a swinging trackway comprising a pair of parallel rods having their inner ends supported for pivotal movement, the forward end of the rods being extended downwardly at an oblique angle and in parallel relation, a connection between the other ends of the rods, a brace rod having one end supported for pivotal movement and its other end connected with the trackway, and a roller carried by the gate and engaged between the rods and adapted to traverse the same and in contact with both.

3. The combination with a gate and a

- roller carried thereby, of a pair of parallel hinged bars engaged by the roller, a connection at the forward end of the rods, a brace connecting the rear ends of the rod, 5 the connection and brace limiting the movement of the roller in either direction, and a brace rod having one end hinged and its other end attached to the forward end of the lowermost hinged rod.
- 10 4. The combination with a gate, of a swinging trackway comprising a pair of parallel rods having their inner ends supported for pivotal movement, the forward ends of the rods being extended at an oblique angle and in parallel relation, a roller car-

ried by the gate and movable between said parallel rods, means to limit the movement of said roller in said rods, and means to prevent the gate from moving accidentally in the trackway when supported at the ends of 20 the rods remote from the forward or oblique angled ends thereof.

In testimony that I claim the foregoing as my own, I have hereto affixed my signature in the presence of two witnesses.

HENRY LAUGHLIN.
